JORDAN PLUG

Dwight E. Jones, Pittsfield, Mass., assignor to
 E. D. Jones & Sons Company, Pittsfield, Mass.,
 a corporation of Massachusetts

Application September 27, 1945, Serial No. 618,914

3 Claims. (Cl. 92—27)

1

This invention relates to improvements in Jordans such as used for treating or acting on paper making material and is directed more particularly to improvements in a plug for Jordans.

The principal objects of the invention are the provision of a Jordan plug which is characterized by novel means for securing the plug knives or bars to the plug.

According to one feature of the invention, the plug knives or bars are supported throughout their length which makes for rigidity while they are locked in the plug in such a way as to obviate shifting and the bars may be removed without disturbing the means for locking them in position.

According to another feature of the invention, the bars or knives are secured to the plug by means which interlock with circumferentially extending bands that are formed by windings of wire or the like as distinguished from prior art solid bands which are heated and shrunk onto the plug. The heating of the bands results in injuriously affecting their physical properties whereas with the band formed according to this invention there results a much stronger structure than heretofore known.

According to the prior art bands which are shrunk in place require that part of the conical surface be cut away so that the bands may be seated. A band expands only slightly upon heating, hence it is necessary to cut a cylindrical surface into the conical surface of the plug for each band seat and this takes away some of the desirable support for the bars. According to this invention, only sufficient length in the plug is cut away for the band itself as the band is formed in the groove provided for it so that the construction provides almost continuous full depth support for the bar.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of a plug construction embodying the novel features of the invention with parts in section for clearness;

Fig. 2 is a sectional view on the line 2—2 of Fig. 1 and through a portion of the periphery of the plug;

2

Fig. 3 is a sectional elevational view on the line 3—3 of Fig. 1; and

Fig. 4 is a view similar to Fig. 2 showing a modified form of the invention.

Referring now to the drawings more in detail, the invention will be fully described.

A plug body is represented by 2 which has shafting 4 that may extend therethrough.

The body has its periphery machined in any well known manner and is provided with longitudinally spaced circumferential grooves 6 and longitudinally extending and circumferentially spaced bar slots 8 and 10.

The grooves 6 are formed to have opposite sides that are perpendicular to the axis of the body while the bottoms thereof are parallel to said axis. These grooves are adapted to receive banding to be described.

The slots 8 preferably extend throughout the length of the body while the slots 10 terminate intermediate the ends of the body. The slots shown are adapted to receive long and short knives or bars 12 and 14 but the longitudinal slots may be arranged and adapted to receive any desired arrangement of bars.

Banding means indicated generally by 20 is carried by each of the grooves 6 and may vary in form and will be described in connection with Figs. 2, 3 and 4.

An inner band 22 is disposed around the groove 6 and may be of bronze, stainless steel or various other metals. The band is preferably cut so that when in place in the groove its adjacent ends are slightly spaced apart.

A wire or wires 24 are served around the band 22. To accomplish this the inner end 25 of the wire may extend through the inner band 22 and into a hole provided in the body. The wire is wound around the band to provide several layers and the winding may be done by placing the plug in a lathe or the like. The windings may be applied simultaneously on any number of the inner bands which are disposed in the grooves.

It is desirable that the wire be wound on the band under tension so that the wire layers are very tight and taut and form a strong rigid band. The outer end of a wire may be secured to an adjacent wire by welding, brazing, soldering or the like, as at 27. It is a well known fact that wire is one of the strongest forms in which metal may be prepared and since it is applied under tension there is produced a band that is exceptionally strong and exceptionally tight—both characteristics of which are desirable to hold the bars firmly in their seats.

In the form of the invention shown in Fig. 4, an inner band 30 is wrapped around in a groove similarly to the band 22 and a thin strip of metal is served around said band 30 in layers 32 with the final end secured in any convenient manner such as mentioned above.

It is desired that the banding fit snugly in the grooves to obviate shifting thereof axially of the body and such material for the wire or strip binding may be employed as will provide the desired strength and rigidity of band.

The knives or bars 12 and 14 are formed on their lower edges with upwardly extending slots 34 providing lips or tongues 36, as shown in Figs. 2 and 4.

In assembling the bars and plug the long bars 12 are inserted in their respective slots so that the bands 20 pass upwardly into the slots 34 on the lower edges of the bars, the said lower edges resting on the bottoms of the slots 8. The bars are moved towards the large end of the plug whereby the lips 36 engage beneath the bands. The lips move the bars towards the bottoms of the slots with more or less of a cam action and hold and prevent radial displacement of the bars relative to their slots.

An end cap 40 fitting over the small end of the plug abuts the ends of the bars 12 and is held in place by screw means indicated by 42. This is a desired construction inasmuch as it covers up the end of the plug and the end of the bars and protects the end of the wood spacers. However, for the purposes of construction this cap may be omitted and in its place an ordinary shrink ring may be used.

An end plate 38 is secured to the large end of the plug by any convenient means and may take any form desired.

Filler members 44 of wood are inserted between the bars and the short bars 14 are inserted in their slots and moved rearwardly for the action of the lips 36. Then blocking members 46 are inserted to prevent endwise movement of said bars 14. Finally filler members 48 are inserted. The filler members are driven inwardly from the large end of the plug so that grooves in the sides thereof receive spurs 48' on opposite sides of the bars.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A plug for a Jordan or the like comprising in combination, a body in the form of a cone an outer surface tapering from a small to a relatively larger end and said surface provided with cutter bar slots and banding grooves, said bar slots formed in and extending longitudinally of the body and being circumferentially spaced therearound, said banding grooves intersecting said bar slots and being continuous and extending circumferentially of the body and being spaced longitudinally thereof and having flat bottoms disposed in parallelism with the longitudinal axis of the body and provided with spaced

opposite sides spaced longitudinally of the body and disposed at right angles to said axis, substantially flat and relatively rigid inner band members extending around said grooves having inner surfaces and opposite sides contiguous with the bottoms and opposite sides thereof, outer banding in said grooves including a member having a plurality of continuous uninterrupted convolutions served under tension about said inner band member with outer convolutions thereof abutting opposite sides of the grooves and having an outer end portion secured to said convolutions, and single cutter bars in and filling said slots having openings spaced along their inner edges formed to provide lips extending towards the larger end of the body engageable with inner sides of said inner band members, all adapted and arranged whereby the inner band members and outer bandings are held against axial movements relative to the body by the opposite sides of the grooves and the bars are held in their slots against radial movement by the lips thereof in engagement with the inner band members.

2. A plug for a Jordan or the like comprising in combination, a body in the form of a cone having an outer surface tapering from a small to a relatively larger end and said surface provided with cutter bar slots and banding grooves, said bar slots formed in and extending longitudinally of the body and being circumferentially spaced therearound, said banding grooves intersecting said bar slots and being continuous and extending circumferentially of the body and being spaced longitudinally thereof and having flat bottoms disposed in parallelism with the longitudinal axis of the body and provided with spaced opposite sides spaced longitudinally of the body and disposed at right angles to said axis, substantially flat and relatively rigid inner band members extending around said grooves having inner surfaces and opposite sides contiguous with the bottoms and opposite sides thereof, outer banding in said grooves including a member having a plurality of continuous uninterrupted convolutions served under tension about said inner band member with outer convolutions thereof abutting opposite sides of the grooves and having an outer end portion secured to said convolutions, and single cutter bars in and filling said slots having openings spaced along their inner edges formed to provide lips extending towards the larger end of the body engageable with inner sides of said inner band members, all adapted and arranged whereby the inner band members and outer bandings are held against axial movements relative to the body by the opposite sides of the grooves and the bars are held in their slots against radial movement by the lips thereof in engagement with the inner band members, said outer banding member having an inner end extending through the inner band member and in engagement with the body.

3. A plug for a Jordan or the like comprising in combination, a body in the form of a cone having an outer surface tapering from a small to a relatively larger end and said surface provided with cutter bar slots and banding grooves, said bar slots formed in and extending longitudinally of the body and being circumferentially spaced therearound, said banding grooves intersecting said bar slots and being continuous and extending circumferentially of the body and being spaced longitudinally thereof and having flat bottoms disposed in parallelism with the longitudinal axis of the body and provided with spaced

opposite sides spaced longitudinally of the body and disposed at right angles to said axis, substantially flat and relatively rigid inner band members extending around said grooves having inner surfaces and opposite sides contiguous with the bottoms and opposite sides thereof, outer banding in said grooves including a member having a plurality of continuous uninterrupted convolutions served under tension about said inner band member with outer convolutions thereof abutting opposite sides of the grooves and having an outer end portion secured to said convolutions, and single cutter bars in and filling said slots having openings spaced along their inner edges formed to provide lips extending towards the larger end of the body engageable with inner sides of said inner band members, all adapted and arranged whereby the inner band members and outer bandings are held against axial movements relative to the body by the opposite sides

19
20

of the grooves and the bars are held in their slots against radial movement by the lips thereof in engagement with the inner band members, and a cap member secured to the small end of the body engaging the ends of said bars and urging them towards the larger end of the body.
